DESIGN FOR A CURTAIN BRACKET

Norman W. White, Longport, N. J.

Application March 29, 1945, Serial No. 118,752

Term of patent 14 years

(Cl. D21—1)

To all whom it may concern:

Be it known that I, Norman W. White, a citizen of the United States, residing at Longport, New Jersey, have invented a new, original, and ornamental Design for a Curtain Bracket, of which the following is a specification, reference being had to the accompanying drawing, forming part thereof.

Figure 1 is a front elevational view of a curtain bracket showing my new design.

Figure 2 is an end elevational view;
Figure 3 is a top plan view; and
Figure 4 is a rear elevational view.

I claim:

The ornamental design for a curtain bracket, as shown.

NORMAN W. WHITE.
